UNITED STATES PATENT OFFICE.

JAMES E. LOSHBOUGH, OF ELKHART, INDIANA, ASSIGNOR, BY MESNE ASSIGNMENTS, TO STURGIS STEEL GO-CART COMPANY, OF STURGIS, MICHIGAN.

BABY-CARRIAGE.

No. 882,901.

Specification of Letters Patent. Patented March 24, 1908.

Application filed May 16, 1907. Serial No. 373,924.

To all whom it may concern:

Be it known that I, JAMES E. LOSHBOUGH, a citizen of the United States, residing at the city and county of Elkhart, State of Indiana, 5 have invented certain new and useful Improvements in Baby-Carriages, of which the following is a specification.

This invention relates to improvements in baby-carriages.

10 It relates particularly to improvements in folding baby-carriages, and is especially designed and adapted for use on the folding baby-carriage shown and described in the application of Otto Kurz, filed Dec. 20th, 15 1906, Serial No. 348,823, and I have shown it embodied in such a structure although it is applicable for use in various other structures.

The main objects of this invention are, first, to provide an improved baby-carriage 20 in which the wheels are adapted to fold inwardly when the structure is collapsed, and, at the same time, one in which the wheels are very rigidly supported in their erected position; and second, to provide in a baby-carriage an improved means for holding the 25 parts in their collapsed or folded position.

Further objects, and objects relating to structural details, will definitely appear from the detailed description to follow.

30 I accomplish the objects of my invention by the devices and means described in the following specification.

The invention is clearly defined and pointed out in the claims.

35 A structure embodying the features of my invention is clearly illustrated in the accompanying drawing, forming a part of this specification, in which,

Figure 1 is a side elevation of a structure 40 embodying the features of my invention, the wheels on one side being removed; Fig. 2 is a detail view partially in section on a line corresponding to line 2—2 of Fig. 1, the locking or bracing means for the wheel supports only 45 being illustrated; Fig. 3 is an enlarged detail section taken on a line corresponding to line 3—3 of Fig. 1; Fig. 4 is an enlarged detail section taken on a line corresponding to line 4—4 of Fig. 1, showing the means for 50 holding the parts in their collapsed position; Fig. 5 is a detail side elevation of a structure in its collapsed position, parts being broken away to better show their form and arrangement; and Fig. 6 is a detail side elevation

showing the locking means for the levers 9, 55 the locking means being shown in its disengaged position.

In the drawing, the sectional views are taken looking in the direction of the little arrows at the ends of the section lines, and 60 similar numerals of reference refer to similar parts throughout the several views.

Referring to the drawing, 1 represents the running gear frame. The handle 2 is pivotally secured at the rear end of the running gear frame by means of the pivots 3. On each of the side bars of the running gear frame are clip-like hangers 4 for the wheel supports 5. A cross-piece 4' is preferably provided for the side bars of the running gear frame at the rear thereof; see Fig. 2. The wheel supports 5 are preferably formed of rods having downwardly-projecting wheel carrying arms 6 which are provided with suitable journals 7 for the wheels. The wheel supports are pivotally supported in the hangers, so that they are free to swing therein to permit the wheels to be folded upon each other under the running gear frame. The wheel supports 5 are provided 80 with offsets, forming crank-like arms 5', the offsets being preferably inclined downwardly toward the rear.

Pivoted to the side bars of the running gear by pivots 12, which are located above 85 the arms 5' of the wheel supports, is a pair of levers 9, their lower ends projecting downwardly below and preferably on the outside of the arms, as clearly appears from the drawing. On the lower ends of the levers 90 are loops 11 adapted to embrace the arms 5' of the wheel supports. When the levers 9 are actuated, these loops engage the crank-like arms and serve to positively swing the wheel supports in and out to collapse or erect 95 them. The lower ends of the levers are preferably connected by a suitable cross-piece 10, indicated by dotted lines in Fig. 1. The levers 9 are preferably connected at their upper ends to the handle 2 by means of the links 100 13, which are adapted to serve as side pieces for the seat, so that by manipulating the handle, the levers are actuated and thereby the wheels collapsed or erected. The links are connected to the handle by means of suitable 105 clips, as 14. The levers are preferably locked and the structure thereby held in its erected position by means of the locking bar

21, which is pivoted on the running gear frame at 23, and connected to the levers 9 by means of the links 22. When the locking bar is pushed down into its lower position in front of the seat, as is shown in Fig. 1, the parts are locked but may be released by lifting the locking bar to the position shown in Fig. 6.

The seat 19 is supported at its forward end 10 by a suitable cross-piece 20 pivoted on the levers 9 and the link-like members 20' pivotally connected thereto and to the running gear frame. The seat is provided with a back 24, which is pivoted thereto and adapted 15 to fold over on the seat when the structure is collapsed. The upper end of the seat is supported by a link 25 which is engaged in a suitable loop 26 on the back of the seat, so that the back may be adjusted. These parts 20 are all preferably substantially such as are illustrated and described in the application for patent hereinbefore referred to.

The wheel supports are braced and rigidly held in their erected or extended position by 25 means of the lever-like braces 15, which are pivoted on the running gear frame at 16, the lower ends of the braces being preferably connected by a cross-piece or brace 15'. On the wheel-carrying arms 6, I arrange forked 30 clips 17, with which the braces are adapted to engage when swung down into the position illustrated in Fig. 2, or when the carriage is in its erected position. The upper ends of these braces are connected by the link 18 to 35 the levers 9, so that, when the carriage is erected, the wheel supports are automatically engaged by these braces 15. When the carriage is collapsed, these braces are thrown up into the position shown in Fig. 5. By this 40 means, the rear wheel supports are braced at their lower ends, so that they are very rigid. It is obvious that the rear wheels carry the great part of the load and strain in use.

To hold the structure in its collapsed position, I provide a pair of upwardly-projecting 45 spring catches 27, which are adapted to engage the links 13, when the structure is in its collapsed position—see Fig. 5—holding them in position. While this effectively holds the 50 parts in their collapsed position, they may be readily disengaged without the manipulation of the catch.

By arranging my improved locking or 55 bracing mechanism for the wheel supports as I have illustrated, the structure is made very rigid, and the parts are automatically brought into position in erecting the carriage.

I have illustrated and described my improvement in detail in the form preferred by 60 me on account of the structural simplicity, and economy. I am, however, aware that it is capable of considerable variation in structural details without departing from my invention.

65 Having thus described my invention, what

I claim as new and desire to secure by Letters Patent is:

1. In a collapsible carriage, the combination with the running gear frame, of wheel supports pivotally mounted on said running gear frame, said wheel supports having downwardly-extending wheel carrying arms; a pair of levers pivotally secured to said frame and connected to said wheel supports, whereby said wheel supports are folded inwardly or erected by the actuation of the said levers; means for locking said levers in their erected position; a pair of braces pivoted on said frame; connecting links for the upper ends of said braces to said wheel support actuating levers; a cross piece connecting the lower ends of said braces; and forked clips on said wheel-carrying arms of said wheel supports adapted to receive said braces when the parts are in their erected position, for the purpose specified. 75 80 85

2. In a collapsible carriage, the combination with the running gear frame, of wheel supports pivotally mounted on said running gear frame, said wheel supports having downwardly-extending wheel carrying arms; a pair of levers pivotally secured to said frame and connected to said wheel supports, whereby said wheel supports are folded inwardly or erected by the actuation of the 90 said levers; a pair of braces pivoted on said frame; connecting links for the upper ends of said braces to said wheel support actuating levers; a cross piece connecting the lower ends of said braces; and forked clips 95 on said wheel-carrying arms of said wheel supports adapted to receive said braces when the parts are in their erected position, for the purpose specified. 100 105

3. In a collapsible carriage, the combination with the running gear frame, of wheel supports pivotally mounted on said running gear frame, said wheel supports having downwardly-extending wheel carrying arms; a pair of levers pivotally secured to said 110 frame and connected to said wheel supports, whereby said wheel supports are folded inwardly or erected by the actuation of the said levers; means for locking said levers in their erected position; a pair of braces pivoted on said frame; connecting links for the upper ends of said braces to said wheel support actuating levers; and forked clips 115 on said wheel-carrying arms of said wheel supports adapted to receive said braces when the parts are in their erected position, for the purpose specified. 120 125 130

4. In a collapsible carriage, the combination with the running gear frame, of wheel supports pivotally mounted on said running gear frame, said wheel supports having downwardly-extending wheel carrying arms; a pair of levers pivotally secured to said frame and connected to said wheel supports, whereby said wheel supports are folded in- 130

wardly or erected by the actuation of the said levers; a pair of braces pivoted on said frame; connecting links for the upper ends of said braces to said wheel support actuating levers; and forked clips on said wheel carrying arms of said wheel supports adapted to receive said braces when the parts are in their erected position for the purpose specified.

10 5. In a collapsible carriage, the combination with the running gear frame, of wheel supports pivotally mounted on said running gear frame; a pair of levers pivotally secured to said frame and connected to said 15 wheel supports, whereby said wheel supports are folded inwardly or erected by the actuation of said levers; means for locking said levers in their erected position; a pair of braces pivoted on said frame adapted to engage said wheel supports when erected; a cross-piece connecting the lower ends of said braces; and connecting links for the upper ends of said braces to said wheel support actuating levers, for the purpose specified.

25 6. In a collapsible carriage, the combination with the running gear frame, of wheel supports pivotally mounted on said running gear frame; a pair of levers pivotally secured to said frame and connected to said 30 wheel supports, whereby said wheel supports are folded inwardly or erected by the actuation of the said levers; means for locking said levers in their erected position; a pair of braces pivoted on said frame adapted to engage said wheel supports when erected; and connecting links for the upper ends of said braces to said wheel support actuating levers, for the purpose specified.

35 7. In a collapsible carriage, the combination with the running gear frame, of wheel supports pivotally mounted on said running gear frame; a pair of levers pivotally secured to said frame and connected to said wheel supports, whereby said wheel supports are folded inwardly or erected by the actuation of the said levers; a pair of braces pivoted on said frame adapted to engage said wheel supports when erected; a cross piece connecting the lower ends of said 45 braces; and connecting links for the upper ends of said braces to said wheel support actuating levers, for the purpose specified.

50 8. In a collapsible carriage, the combination with the running gear frame, of wheel supports pivotally mounted on said running gear frame; a pair of levers pivotally secured to said frame and connected to said wheel supports, whereby said wheel supports are folded inwardly or erected by the actuation 55 of the said levers; a pair of braces pivoted on said frame adapted to engage said wheel supports when erected; and connecting links for the upper ends of said braces to said wheel support actuating levers, for the purpose 60 specified.

9. In a collapsible carriage, the combination of a running gear frame; wheel supports pivotally mounted on said frame; means for collapsing or erecting said wheel supports; a pair of braces pivoted on said frame adapted 70 to engage said wheel supports when erected; and connections for said braces to said wheel support actuating means whereby said braces are automatically brought into their engaging position or collapsed in erecting or collapsing the carriage.

10 10. In a collapsible carriage, the combination of a running gear frame; wheel-supports pivotally mounted on said running gear frame, said wheel-supports having downwardly-extending wheel-carrying-arms; a pair of braces pivoted on said frame, adapted 80 to engage said wheel-support carrying-arms, when in their erected position; a cross-piece connecting the lower ends of said braces, and means for erecting or collapsing said wheel-supports, connected to said braces, whereby said braces are automatically 85 swung into or out of their engaging position in erecting or collapsing the carriage.

11 11. In a collapsible carriage, the combination of the running gear frame; wheel-supports pivotally mounted on said running-gear frame, said wheel-supports having downwardly-extending wheel carrying-arms; a pair of levers pivotally secured to said frame and connected to said wheel-supports, whereby said wheel-supports are folded inwardly or erected by the actuation of said 90 levers; a pair of braces pivoted on said frame, adapted to engage said wheel-supports when in their erected position, said braces being adapted to be swung inside of said frame when collapsed; and connections from said levers to said braces whereby said braces are automatically brought into engaging position or collapsed in erecting or collapsing the carriage.

12 12. In a collapsible carriage, the combination with a running gear frame, including a pair of side-bars, of wheel-supports pivotally mounted on said frame; a pivoted brace, pivoted on said frame, adapted to engage the said wheel-supports at their lower ends when they are erected or to swing up between the side-bars of the frame when collapsed; and means for erecting or collapsing the said wheel-supports connected to said brace, whereby said brace is automatically swung into its engaging position or collapsed upon 110 the erecting or collapsing of the carriage.

13 13. In a collapsible carriage, the combination with a running gear frame, including a pair of side-bars, of wheel-supports pivotally mounted on said frame; a pivoted brace, pivoted on said frame, adapted to engage the said wheel-supports when they are erected or to swing up between the side-bars of the frame when collapsed; and means for erecting or collapsing the said wheel-supports con- 125 130

4
nected to said brace, whereby said brace is automatically swung into its engaging position or collapsed upon the erecting or collapsing of the carriage.

5. 14. In a collapsible carriage, the combination with the running gear frame, of wheel supports pivotally mounted on said running gear frame; a handle pivotally connected at the rear end of said running gear frame; levers pivoted on said running gear frame, adapted, upon actuation, to fold said wheel supports inwardly or erect the same; connecting links for the upper ends of said levers to said handle; and a spring catch on said 10 running gear frame adapted to engage said links when the parts are in their folded position, for the purpose specified.
15. 15. In a collapsible carriage, the combina-

tion with the running gear frame, of wheel supports pivotally mounted on said running gear frame; a handle pivotally connected at the rear end of said running gear frame; connections for said handle to said wheel supports whereby they are folded or erected by the actuation of the handle; and a spring catch on said running gear frame, adapted to engage the parts to retain them in their folded position.

In witness whereof, I have hereunto set my hand and seal in the presence of two witnesses.

JAMES E. LOSHBOOUGH. [L. s.]
